UNITED STATES PATENT OFFICE.

JAMES H. CARY, OF BOSTON, MASSACHUSETTS, ASSIGNOR TO THE CARY TELEPHONE SIGNAL COMPANY, OF PORTLAND, MAINE.

TELEPHONE SIGNALING APPARATUS.

SPECIFICATION forming part of Letters Patent No. 310,379, dated January 6, 1885.

Application filed January 11, 1884. (No model.)

To all whom it may concern:

Be it known that I, JAMES H. CARY, of Boston, in the county of Suffolk and State of Massachusetts, have invented certain Improvements in Telephone Signaling Apparatus, of which the following is a specification.

The object of my invention is to furnish a simple and sure means of calling any one station out of several located on the same line without causing any signal to be sounded at the other stations on the same line.

The invention consists in an improved signaling system, including a series of individual signals, each requiring an operating-current of electricity differing in quality, as herein-after described, from those required to operate the other signals, and means for sending through the circuit as many different qualities of electric current as there are instruments in the series.

In the embodiment of my invention herein-after described, the different signals or instruments are operated by variations in the strength, polarity, and duration of the current.

I will now proceed to describe each of the signals in detail and show their relations to each other, together with calling devices for operating the same.

Of the accompanying drawings, forming a part of this specification, Figure 1 represents a perspective view of one of the instruments belonging to what I term the "first class," said class being indicated by the numerals 1 2 3 4 in Fig. 4. These instruments are caused to operate by constant battery or magneto currents of a definite polarity and strength, each instrument requiring a current of different quality from that required by the others.

Fig. 2 is a plan view of the same instrument. Fig. 3 is a perspective view with parts broken away, showing the circuits through the instrument, and bell attached. Fig. 4 is a diagram showing a line provided with seven stations—four of the first class with bell attached on local circuit, two bells of the pattern ordinarily known as "bipolar bells," operated by direct current in main line, and the seventh a regular vibrating magneto-bell; also the connection of the batteries and generator and

keys with the line, whereby the various qualities of current are sent to line.

The instrument shown in Figs. 1, 2, and 3 is a form of relay, whereby the local battery and bell are thrown in connection by the action of the main battery at the central office upon the electro-magnet and armatures operated thereby when the proper current is sent to line. In said figures, M is an electro-magnet. A is a neutral armature having an upwardly-projecting arm, a. B is a permanent magnet freely suspended on screw b and acting as a polarized armature. C is a stiff spring secured upon insulating-block F, and adapted to make contact with the top of permanent magnet B, and complete the local circuit upon the passage of a current of the proper polarity. D is a spring fastened upon the back board, E, and adapted to make contact with the rod a, attached to the armature A, when the proper current is sent to line. G is a bent spring adapted to bear upon the permanent magnet B with very light pressure to cause it to break contact with spring C when no current is sent to line, but of insufficient strength to interfere with the proper action of the current upon the magnet B. H is a post on which are mounted springs C and G and permanent magnet B. I is a retractile spring adapted to act on arm a, thus withdrawing the armature A from the electro-magnet when the current has ceased to flow. J is an adjusting-screw for regulating the tension of spring I. K and K' are springs secured upon the back-board for the purpose of making contact with the angle-pieces L L', which are fastened to the sides of the box, and from which the wires d d extend to the bell-magnet N.

The operation of the instruments of the first class is as follows: The polarized armature B is adapted to be attracted against the force of the spring G by a light battery-current of proper polarity, not of sufficient strength to attract the neutral armature. Such a current being sent, the attraction of the polarized armature will cause the upper end of said armature to make contact with spring C, which will complete the local circuit through the post H and metal frame and standards S, pivots P, armature A, rod a, spring D, wire 100

e, spring *K*, angle-piece *L*, wire *d*, bell-magnet *N*, wire *d'*, angle-piece *L'*, spring *K'*, wire *f*, post 2, wire *j*, to local battery, thence by wire *k*, post 3, wire *g*, to spring *C*, thus completing the local-battery circuit and ringing the bell *O*.

When the apparatus is operated as above described, the spring *D* is normally in contact with the rod *a*, as shown in Figs. 1 and 10 3, when the neutral armature is not attracted by the magnet *M*. When a heavier current is thrown to line sufficient to attract the neutral armature, the contact between said armature and the spring *D* is broken, so that notwithstanding 15 the current attracting the neutral armature might be the proper polarity to attract the polarized armature also, the bell would not be rung. Another similar instrument in the same circuit may be adapted to 20 be operated only by a current of sufficient strength to attract the neutral armature by simply adjusting the spring *D* so that when the instrument is in its normal condition or when the light current is sent the contact 25 between rod *a* and spring *D* would be broken, as shown in Fig. 2, until a current of sufficient strength was sent to line to attract the armature *A*, when the rod *a* and spring *D* would be thrown in contact, thus completing 30 the local circuit, when a current of the proper polarity also is used to attract the polarized armature, as before. Thus it will be seen two bells are adapted to be operated by variations 35 in the strength of the current, the polarity being the same for each bell, each bell responding to its own operating-current, but not to that which operates the other. Two additional instruments similarly constructed may be adapted to be operated respectively 40 by stronger and weaker currents of opposite polarity to those required to operate the two above described. To this end it will be necessary only to make the line-wire enter the instruments of the second pair on the side opposite to that on which it entered the instruments of the first pair. For instance, if the line-wire as it comes from the operating or central office enters in the first pair of instruments at the left or post *I'*, in the second pair 45 it should enter at post *4'*, and the line out would be from post *I'*. Four instruments are thus provided, two of which are operated by weak currents of opposite polarity, and the other two by stronger currents of opposite 50 polarity. The key-boards shown in *A*² and *B*², Fig. 4, are of the ordinary pattern known as "reversing-keys," and enable the currents of either polarity to be sent to operate the instruments, as above described. Another key-board, *C*², of special construction, is provided, adapted to control the currents from a generator, *G*², to operate the additional instruments, 5, 6, and 7, in the same line-circuit. The key *K*² is in the form of a swinging spring-65 switch. When in its normal position, it bears against the back contact or arc, *d'*, which is connected by wire *e'* to earth, or, as is shown

by the diagram, to a connection at point *E'* with wires *t* and *t'*, thus completing a metallic circuit. The method of operation in this 70 case will be to depress the key upon anvil 1", 2", or 3", respectively, according to the nature of the current desired to be sent to line. The generator *G*² is a magneto-generator of the Siemens armature pattern, provided with the 75 usual brushes for taking the alternating current from the spindles at either end; also with an eccentric, *h*², for sending the positive or negative current through spring *i'* or *j'*, respectively, according to which anvil the key *K*² is depressed upon, thus completing circuit through wires *a'* or *c'* and key *K*² to line. Bells 5, 6, which are of the ordinary bipolar kind, will respond to currents thus sent, respectively, of positive or negative polarity, rapidly 85 broken. Bell 7, which is an ordinary vibrating magneto-bell, will respond to a rapidly-alternating current of less strength, the strength of the alternating current being diminished by the resistance-coil *R*², which is thrown into 90 the circuit only when bell 7 is to be operated, thus preventing the alternating current from operating bells 5 and 6. The rapidly-broken current as sent from the generator by eccentric *h*² will have no effect upon bells 1, 2, 3, 95 and 4. The reversal of the polarity of the current would cause one tap on bell 7; but that would be readily distinguished from a continuous peal, which constitutes an ordinary signal. The bells 1, 2, 3, and 4 may be operated by magneto-currents, instead of by battery-currents, as will be described and claimed in a future application. 100

I am aware that it is not new to operate the various signaling-instruments on a line by variations in the polarity or strength of the current, and I do not claim such, broadly. 105

I claim—

1. In a telephone signaling system, a signaling apparatus consisting of an electro-magnet, a polarized armature therefor, a spring-contact for the same, a neutral armature carrying a contact-arm, and springs and connections, substantially as described, the arrangement being such that a light current of proper polarity may operate the polarized armature only, while a heavy current may operate the neutral armature alone, or both the polarized and neutral, according to its direction, as set forth. 110

2. In a telephone signaling system, a signaling apparatus having an electro-magnet, a polarized armature, and a neutral armature therefor adapted to respond, respectively, to weaker and stronger current, a contact-spring, as *C*, adapted to make contact with the polarized armature when the latter is attracted by a current of proper polarity, a contact-spring, as *D*, adapted to be adjusted so as to make contact with an arm on the neutral armature, either when the latter is separated from the poles of the magnet or attracted thereto, and connections, substantially as described, whereby a local circuit may be completed either by 115 120 125 130

the attraction of the polarized armature alone, or by the simultaneous attraction of both armatures by currents of proper polarity, as set forth.

5 3. The combination of a generator adapted to send interrupted currents of either polarity, or currents of alternating polarity, with the key K² and connections whereby either of said currents may be sent to line, a series of signals 10 adapted to be operated, respectively, by interrupted currents of positive polarity, interrupted currents of negative polarity, and weakened currents of alternating polarity, and a resistance whereby the currents of alternating 15 polarity are weakened, as set forth.

4. The combination, with a generator or generators and circuit-controlling devices whereby currents of varying polarity and strength may be sent to line, of a generator and switch 20 apparatus whereby interrupted currents of either or alternating polarity may be sent to line, and a series of signaling-instruments, each

adapted to be operated by only one of said currents, as set forth.

5. The combination, with a voltaic battery 25 and circuit-controlling devices whereby currents of varying strength and polarity may be sent to line, of a generator and circuit-controller whereby magnetic currents of either polarity or magnetic currents of alternating 30 polarity may be sent to line, and a series of signaling devices, each adapted to respond to one, and only one, of said currents, substantially as described.

In testimony whereof I have signed my name 35 to this specification, in the presence of two subscribing witnesses, this 4th day of January, 1884.

JAMES H. CARY.
